DINNER PLATE

Simon H. Slobodkin, New York, N. Y., assignor to
Canonsburg Pottery Company, Canonsburg,
Pa., a corporation of Pennsylvania

Application September 26, 1950, Serial No. 12,353

Term of patent 7 years

(Cl. D44—15)

To all whom it may concern:

Be it known that I, Simon H. Slobodkin, a citizen of the United States of America and a resident of New York, in the county and State of New York, have invented a new, original, and ornamental Design for a Dinner Plate, of which the following is a specification, reference being had to the accompanying drawing, forming a part thereof, in which:

Fig. 1 is a top plan view of a dinner plate, showing my new design;

Fig. 2 is a side elevation thereof with part shown in section in the plane of the line 2—2 of Fig. 1; and

Fig. 3 is a bottom plan view of the same.

I claim:

The ornamental design for a dinner plate, as shown.

SIMON H. SLOBODKIN.
